PORTABLE AUTOGRAPHIC REGISTER

Louis F. Hageman, Lewiston, N. Y., assignor to
American Sales Book Company, Inc., Niagara
Falls, N. Y., a corporation of Delaware

Application August 1, 1941, Serial No. 405,070.

16 Claims. (Cl. 282—3)

This invention relates to improvements in devices for facilitating the making of inscriptions on record strips or the like, and more particularly to improved mechanism for controlling, positioning and aligning the record strips of the long continuous traveler type for receiving inscriptions upon a writing platen. The improvements are disclosed as embodied in an autographic register of the portable type carrying its own record supplies and being small and light so as to be readily carried in the hand of the user.

It is a general object of the invention to provide for inscription devices of the class mentioned, an improved record strip controlling and aligning mechanism that is effective in aligning and positioning the record strips in writing position upon the platen, and that embodies few moving parts and is light and compact and suitable for installation upon inscribing apparatus of the portable type, so that the latter can be made very light and compact and suitable for holding in the hand during the making of inscriptions, and inexpensive in production costs.

A further object of the invention is to provide an improved arrangement of strip co-operative controlling and aligning means, adapted to be controlled for engagement and disengagement with the record strips by a simple and effective control device adapted to be actuated by the operator in the act of reaching for the free ends of the record strips preparatory to pulling out an inscribed set of record leaves and bringing the next set of blank record leaves into inscription position upon the writing platen.

Another object of the invention is to provide a record strip controlling device for inscribing apparatus of the class mentioned and embodying an improved strip guiding and severing member movably mounted and operatively connected to strip controlling and aligning devices, such for example, as strip aperture engaging pins, so as to automatically free the strips to advancement over the writing platen when the strip severing member is moved to expose the free ends of the strips so that they can be grasped and pulled out by the operator.

According to an important feature of the invention, a longitudinally reciprocating slide or carriage supports the strip controlling pins and also supports the strip severing bar which guides the forward ends of the strip, whereby the strip controlling pins are moved to strip disengaging position when the strip severing bar is moved rearwardly by the operator in the act of reaching for and grasping the free ends of the record

strips to pull them forwardly over the writing platen.

A further object of the invention is to provide an improved transfer sheet support for supporting one or a plurality of transfer sheets in transfer relation with the record strips when in writing position upon the platen, and providing for transferring to the underlying record strips the inscriptions made upon the top or original record strip.

Other objects of the invention will be in part pointed out in the following detailed description of an illustrative but preferred embodiment of the invention, and will be in part obvious as the disclosure proceeds.

The invention accordingly comprises the features of construction, combination of elements, and arrangement of parts, which will be exemplified in the construction hereinafter set forth and the scope of the application of which will be indicated in the claims.

For a more comprehensive disclosure of the nature, objects and advantages of the invention, reference is had to the following detailed description of the illustrative embodiment, and to the accompanying drawings in which:

Fig. 1 is a perspective view of an autographic register of the portable type, embodying the invention and having the record strips in inscription receiving position upon the writing platen;

Fig. 2 is an enlarged plan view of the register shown in Fig. 1;

Fig. 3 is a central longitudinal vertical section through the register shown in Fig. 2;

Fig. 4 is a transverse vertical section taken approximately on the line 4—4 of Fig. 3 looking in the direction of the arrows;

Fig. 5 is a transverse vertical section approximately on the line 5—5 of Fig. 3 looking in the direction of the arrows;

Fig. 6 is a fragmentary enlarged plan and sectional view showing details of the record strip controlling mechanism, and

Fig. 7 is a detail perspective view of the forward end of the strip controlling carriage, embodying the tear-off bar and carriage operating element.

Referring to the drawings for a detailed description of the illustrative embodiment of the invention there shown, the improvements are applied to an autographic register of the portable type having a casing 10 of box-like formation providing an interior space for housing a supply of record material. The casing may be constructed of any preferred material, such for

example, as sheet metal or any of the well-known plastic materials.

The forward end of the casing is preferably offset forwardly at its lower part, as indicated at 11, so as to provide an extension of the housing for the record supply. The upper wall 12 of this offset portion is inclined rearwardly, leaving a space thereabove for the accommodation of parts of the operating mechanism, as later fully described. Rising above the inclined wall 12 is the wall 13 which completes the forward end wall.

At the rearward end of the casing is an opening or passageway for the reception of the supply of record material and this passageway is closed by a swinging door or cover 14 pivoted adjacent its lower edge to the casing as indicated at 15. This cover is provided with a spring latch 16 which automatically engages in holding position when the cover is swung into closed position. The top wall 17 of the casing is positioned above the bottom wall thereof extending rearwardly from the front wall 13 and forming a record strip supporting writing platen having a flat smooth writing surface upon which the record strips are supported for inscription.

Record strips S of the long continuous traveler type are drawn forwardly from the record strip supply S' housed within the casing into writing position upon the platen 17. The supply S', as shown, is preferably in the form of a flat zigzag folded pack in which one, two, three or more long continuous record strips are compactly folded. Three such record strips are shown in the drawings but more or less than three can be readily used. One of the principal objects of this invention is to control the movement of these record strips into writing position upon the platen, and to align and position them thereon and to provide for feeding the inscribed portions or sheets forwardly from their writing position so that they can be severed from the continuous strips, and at the same time bring the succeeding sets of blank record sheets into writing position upon the platen.

For the purpose of effecting this control of the record strips a longitudinally reciprocating carriage or frame indicated generally at 18 is mounted upon the casing and operatively connected to strip controlling devices. As shown, this carriage is in the form of a longitudinally reciprocating sliding frame having supporting longitudinal side members or plates 19 mounted in upper offset portions 20 of the side walls of the casing and extending throughout the major length of the casing. A transverse frame member or plate 21 connects the rearward extremities of the side members 19. Strip controlling members in the form of projections or pins 22 are securely attached to the transverse frame member 21 extending longitudinally inwardly therefrom in position to engage with apertures S² formed at regular longitudinal intervals along the record strips S. The longitudinal spacing of the control apertures S² is ordinarily the same as the length of the record leaves of the record strips. Each record leaf is ordinarily provided with a printed blank form S³ appropriate for the desired inscriptions. It will be noticed that the control pins 22 have their major axes or lengths projecting forwardly from the supporting transverse frame member 21 so as to enter the strip apertures as the strips are turned in their movements from the supply compart-

ment into writing position upon the platen 17.

Substantially at its forward extremity the controlling carriage or frame 18 has a transverse frame member 23 extending between the forward ends of the side frame members 19 and connected thereto. Thus the frame or carriage 18 is substantially rectangular having longitudinal side frame members and transverse end frame members. The side frame members 19 extend forwardly beyond the upright end plate 13, the transverse frame member 23 thus being positioned at the exterior of the casing so as to be readily accessible. The transverse frame member 23 has an elongated transversely extending slot 24 forming a strip passageway substantially in longitudinal alignment with the writing surface of the platen 17. Although the frame member 23 may be of integral structure and attached at its opposite ends to the longitudinal frame members 19, it is shown as embodying an upper plate 25 having an outwardly turned lower flange 26 adjacent to the passageway 24, and a lower plate 27 having an outwardly turned upper flange 28 adjacent to the lower side of the passageway 24. The upper and lower plates are connected together by upright plates 29 brazed or otherwise attached thereto. The side frame members 19 are turned inwardly at their forward ends forming angularly disposed attaching extensions 30 brazed or otherwise attached to the lower plate 27. The flanges 26 and 28 thus form upper and lower severing edges along which the strips S may be torn. For this purpose the strips may be provided with transverse weakened severance lines S⁴. It will be noted that the transverse frame member or severing bar assembly 23 is positioned in the depression or space above the offset 11 of the casing, and is thus partially housed and protected during its longitudinal movements as later described.

Adjacent to the forward end of the platen 17 and immediately at the rear of the tear-off bar assembly 23 is a transverse thin metallic plate 31 spaced slightly above the adjacent end of the platen, providing a passageway therebeneath through which the strip assembly passes. This transverse plate 31 is connected at its opposite end portions by downwardly turned flanges brazed or otherwise connected to the side walls of the casing. This transverse plate 31 is preferably of resilient metal so as to exert downward yielding pressure upon the strip assembly thus holding the assembly in position with a yielding pressure so as to avoid displacement thereof during operation of the strip controlling mechanism.

Adjacent to the rear end of the platen 17 is a strip guiding element 32 preferably in the form of a guide roller having bearing extensions 33 rotatably supported in down-turned lugs or flanges 34 on the rear end of the platen 17. This guide roller has a smooth peripheral surface around which the record strips pass in an arc of considerable extent adjacent to the controlling pins 22. Also this guide roller is provided with deep peripheral grooves 35 extending entirely around the roller and positioned respectively adjacent to the controlling pins 22. A strip guide 36 is positioned adjacent to the rearward surface of the guide roller 32 having a curved upper part for engagement with the strips to cause them to move closely to the guide surface of the roller and adjacent to the control pins 22. This guide plate 36 is notched at 37 to provide clearance for the con-

trol pins 22. The guide plate 36 has a downward extension 38 by means of which it is attached at its lower edge portion to the swinging cover 14. This extension 38 is normally in upright position thus forming the inner end wall surface for the storage compartment for the supply S'. Upper bracing and supporting members 39 are connected at their inner ends to the upper part of the guide plate 36 and at their outer ends to the wall of the cover 14.

The strip controlling carriage 18 is normally retained in its forward operative position, as shown in Fig. 3, by tensioned coil springs 40 connected at their forward ends to attaching lugs 41 on the register casing and at their opposite ends to pins 42 attached to the side frame members 19 of the carriage. These springs are normally under light tension when the controlling carriage is in its normal position, as shown in Fig. 3, so as to retain said carriage in this position until it is desired to pull the inscribed forward ends of the record strips forward. A horizontal partition 40' spaced below the platen 17 provides a housing for the springs 40.

Transfer sheet supporting blades or arms 43 are pivotally supported at 44 to lugs provided on the outer sides of the casing. In order that the supporting blades can swing free and clear of the platen they are formed with angularly disposed downwardly extending supporting extensions 45. Thus as best seen in Fig. 4, the transfer sheet supporting blades 43 extend transversely of the platen just above the surface thereof. During the time that the strips are being threaded into position the blades can be swung outwardly beyond the pivots 44. The transfer sheets, two in the present instance, can be supported in transfer relation with the record strips by folding the forward edges of the sheets over the blades 43. Spring clips or other attaching means can be used if desired to retain the transfer sheets in position upon the supporting blades.

Operation of the improved mechanism will be clear from the foregoing description, but for clearness and definiteness may be summarized as follows: The supply pad S' of record strips having been loaded into the supply compartment through the rear passageway of the casing, the forward end of the strip assembly is threaded around the rear surface of the guide or guide roller 32, the guide plate 36 being moved rearwardly by opening the rear door 14, and the controlling pins 22 being retracted slightly by rearward pressure upon the forward frame member or severing bar 23. The forward ends of the strips are then led forwardly over the platen, the transfer sheets mounted upon the supporting blades 43 and interleaved in transfer relation with the record strips, while the forward ends of the strips are threaded under the resilient pressure bar 31 and through the strip passageway 24 in the severing bar assembly. As the record strips are pulled forwardly to this position, a pair of apertures S² thereof come into alignment respectively with the controlling pins 22 which thus enter the apertures under the influence of the spring 40 to position and align the strips in correct writing position upon the platen 17. In this connection it will be noted that the movement of the pins 22 in entering and leaving the strip apertures is a unitary movement with the supporting carriage 18. No additional movement of the pins is required, and no additional movable mountings for the pins are needed. The movement of the pins is longitudinal of the major axes thereof,

and the same as the longitudinal movement of the supporting and controlling carriage 18, the pins being positioned so as to enter or leave the apertures merely by moving the carriage. Due to the incidence of the peripheral grooves 32 of the guide roller, the pins can penetrate and enter fully into controlling relation with the record strips at the curved part of the path thereof adjacent to the guide roller. The control pins being positioned at the turn of the strip path, and at the outer or convex side of the turn, only longitudinal movements thereof are necessary for strip engagement or disengagement. By means of this simple but effective arrangement the strips are accurately and easily controlled and aligned in correct writing position upon the platen, while at the same time due to the simplicity of this mechanism very little space is required for its installation, and consequently the portable register can be made very small, light and compact and well adapted for easy handling and making of inscriptions.

After a set of forms has been inscribed upon the platen 17, the operator engages the severing bar assembly 23, which functions as an operating plate or handle, with a finger or thumb and pushes the controlling carriage 18 rearwardly against the tension of the springs 40. This movement withdraws the control pins 22 from the strip apertures and at the same time retracts the severing bar and operating plate 23 thus causing the forward end of the strip assembly to project beyond the bar 23 in position to be grasped by the fingers of the operator. At the same moment that the bar 23 is moved rearwardly, the fingers grasp the protruding end of the strip assembly when the bar reaches its rearward position and the pins 22 are retracted from aperture engaging position. During this movement the resilient pressure bar 31 causes sufficient frictional pressure to prevent any retraction of the strip assembly that might interfere with the projection thereof into grasping position at the outer side of the bar 23. When the bar 23 reaches the rearward position the operator grasps the forward end of the assembly pulling it outwardly to the right, as viewed in Fig. 3, thus moving the apertures S² from alignment with the control pins 22. At the same time the carriage 18 is moved forwardly by the springs 40 so that the free ends of the control pins 22 engage with the turn of the record strips to the rearward of and out of alignment with the apertures S². Continued pull upon the record strips moves them forwardly to bring the next set of forms in writing position upon the platen. Near the end of this movement the next succeeding pair of control apertures S² comes into alignment with the pins 22 which thus enter the apertures under the influence of the springs 40 to position and align the new set of forms in writing position upon the platen. When this movement is completed the severance lines S⁴ will be substantially aligned with the tearing edges 26 and 28, whereupon the inscribed set of forms may be quickly and easily severed by exerting either an upward or a downward tearing pull across either one of these edges. If desired the severance may be effected over these tearing edges without the aid of the weakened lines S⁴.

Since certain changes may be made in the above construction and different embodiments of the invention could be made without departing from the scope thereof, it is intended that all matter contained in the above description or shown in

the accompanying drawings shall be interpreted as illustrative and not in a limiting sense.

Having described my invention, what I claim as new and desire to secure by Letters Patent is:

1. In a device of the character described, in combination, a writing platen, a strip checking device mounted for reciprocating movement longitudinally of said platen into position for automatically engaging and checking strips in aligned position upon predetermined movement thereof on said platen, a movable strip severing device, operative connections between said severing device and said strip checking device to move the latter into strip releasing position upon movement of the former, and a yielding strip support yieldingly engaging the strips adjacent to said strip severing device.

2. In a device of the character described, in combination, a writing platen, strip guiding means to effect a rearwardly disposed turn in the strips, a movably mounted strip checking device positioned adjacent to the rear end of said platen at the outside of said strip turn and automatically engaging the strips substantially at said turn thereof and checking them in aligned position upon the platen upon predetermined movement thereof on said platen, a movable strip severing device positioned adjacent to the front end of said platen, and operative connections between said severing device and said strip checking device to move the latter into strip releasing position upon movement of the former.

3. In a device of the character described, in combination, a writing platen, a strip checking pin positioned adjacent to the rear end of said platen and mounted for reciprocating movement longitudinally of said platen into position for automatically entering and checking the strips in aligned position upon the platen upon predetermined movement thereof on said platen, movable strip severing device positioned adjacent to the front end of said platen, operative connections between said severing device and said strip checking pin to move the latter rearwardly into strip releasing position upon movement of the former, and a yielding strip support yieldingly engaging the strips adjacent to said strip severing device.

4. In a device of the character described, in combination, a writing platen, strip guiding means to effect a turn in the strips, a strip checking device positioned outside of said strip turn for engaging the strips substantially at said turn to check them in aligned position upon the platen upon predetermined movement thereof on said platen, a strip severing device positioned adjacent to the front end of said platen, and a supporting carriage mounted for reciprocation longitudinally of said platen and mounting said checking device and said severing device for bodily movements in unison longitudinally of said platen and for moving said checking device to and from strip checking position.

5. In a device of the character described, in combination, a writing platen, a strip checking device positioned adjacent to the rear end of said platen and automatically engaging and checking the strips in aligned position upon the platen upon predetermined movement thereof on said platen, a strip severing device positioned adjacent to the front end of said platen, said checking device and said severing device being mounted for longitudinal bodily movements in unison so as to move said checking device into strip releasing position by movement of said severing device, and a strip guiding roller about which the strips are turned

adjacent to said checking device and having a peripheral groove in which said checking device is received in strip checking position.

6. In a device of the character described, in combination, a writing platen, a strip checking device positioned adjacent to the rear end of said platen and automatically engaging and checking the strips in aligned position upon the platen upon predetermined movement thereof on said platen, a strip severing device positioned adjacent to the front end of said platen, said checking device and said severing device being mounted for longitudinal sliding movements in unison so as to move said checking device into strip releasing position by movement of said severing device, a strip guiding roller about which the strips are turned adjacent to said checking device and having a peripheral groove in which said checking device is received in strip checking position adjacent to the strip turn, a rear cover for a supply compartment, and a strip guide carried by said cover and positioned adjacent to the groove of said guide roller.

7. In a device of the character described, in combination, a writing platen, a strip checking device positioned adjacent to the rear end of said platen and automatically engaging and checking the strips in aligned position upon the platen upon predetermined movement thereof on said platen, a strip severing device positioned adjacent to the front end of said platen, said checking device and said severing device being mounted for longitudinal sliding movements in unison so as to move said checking device into strip releasing position by movement of said severing device, a strip guiding roller adjacent to said checking device and having a peripheral groove in which said checking device is received in strip checking position, a rear cover for a supply compartment pivotally mounted adjacent to its lower edge, and a strip guide carried by said cover and having its strip guiding edge portion swinging with the cover so as to be positioned adjacent to the groove of said roller when the cover is in closed position.

8. In a device of the character described, in combination, a platen, a carriage mounted for longitudinal reciprocation adjacent to said platen, strip positioning and strip severing devices mounted on said carriage for reciprocation therewith, a strip guide about which said strips are turned adjacent to said strip positioning device, and said positioning device including a strip aperture-engaging pin longitudinally displaceable with said carriage so as to be caused to enter and leave strip apertures at the turn of the strips by longitudinal reciprocation of said carriage.

9. In a device of the character described, in combination, a platen for receiving strips, a carriage mounted for longitudinal reciprocation adjacent to said platen and biased for movement into forwardly disposed operative position, an operating handle having a strip passageway and carried by said carriage at the forward part thereof and biased therewith into said operative position, said handle being movable rearwardly with said carriage upon engagement of the handle by the operator to cause the strips to project through said passageway at the forward side of the handle into position to be grasped, said handle having strip severing edges respectively positioned above and below said passageway, and means for preventing retraction of the strips during said rearward movement of said handle.

10. In a device of the character described, in combination, a platen for receiving strips, a carriage mounted for longitudinal reciprocation ad-

adjacent to said platen and biased for movement into forwardly disposed operative position, an operating handle having a strip passageway and carried by said carriage at the forward part thereof and biased therewith into said operative position, said handle being movable rearwardly with said carriage upon engagement of the handle by the operator to cause the strips to project through said passageway at the forward side of the handle into position to be grasped, said handle having strip severing edges respectively positioned above and below said passageway, means for preventing retraction of the strips during said rearward movement of said handle, means spaced rearwardly of the platen from said handle for causing a turn in the strips, and a strip engaging strip controlling pin mounted on said carriage substantially at the outside of said strip turn for unitary movement with said carriage to and from controlling engagement with the strip substantially at the outside of said strip turn.

11. In a device of the character described, in combination, a platen for receiving strips, means for causing a turn in said strips transverse to said platen, a strip controlling and positioning pin having its longitudinal dimension extending longitudinally of said platen and being mounted for reciprocation longitudinally of the platen with its strip engaging end directed forwardly toward said strip turn, and means for reciprocating said pin longitudinally of the platen to and from controlling engagement with the strips substantially at said turn.

12. In a device of the character described, in combination, a platen for receiving strips, a carriage mounted for reciprocating movements longitudinally of and adjacent to said platen, means for causing a turn in said strips, and a strip controlling and positioning pin mounted on said carriage for longitudinally reciprocating movement therewith, said pin being positioned on said carriage with its end directed forwardly toward said strip turn so as to be moved by said carriage movement through the strips into controlling engagement therewith substantially at said turn.

13. In a device of the character described, in combination, a platen for receiving strips, a carriage mounted for reciprocating movements longitudinally of and adjacent to said platen, means for causing a turn in said strips, a strip penetrating strip positioning member mounted on said carriage for unitary longitudinal reciprocating movements therewith and positioned thereon so as to be moved by said carriage movement into penetrating engagement with the strips substantially at said turn thereof, means for biasing said carriage to cause said strip controlling member to automatically engage the strips in strip controlling relation upon predetermined strip movement on the platen, and an operating member with a strip passageway carried by said carriage and biased therewith into forward operative position and

movable rearwardly upon engagement by the operator to project the strips through said passageway.

14. In a device of the character described, in combination, a platen for receiving strips, a carriage mounted for reciprocating movements longitudinally of and adjacent to said platen, means for causing a turn in said strips, a strip controlling and positioning pin mounted on said carriage for longitudinally reciprocating movement therewith, said pin being positioned on said carriage with its end directed forwardly toward said strip turn so as to be moved by said carriage movement through the strips into controlling engagement therewith substantially at said turn, means for biasing said carriage to cause said pin to automatically engage the strip in strip controlling relation upon predetermined strip movement on said platen, and an operating member with a strip passageway carried by said carriage and biased therewith into forward operative position, and movable rearwardly upon engagement by the operator to project the strips through said passageway.

15. In a device of the character described, in combination, a writing platen for record strips, strip guiding means positioned rearwardly of the platen to effect a turn in the strips transverse to said platen relatively rearwardly thereof, a strip checking device including a strip penetrating member mounted for reciprocation longitudinally of said platen and having its strip engaging extremity directed longitudinally of the platen toward said strip turn so as to engage and disengage the strips upon longitudinal reciprocation of said penetrating member, and yielding means for yieldingly urging said penetrating member into strip penetrating controlling position at said strip turn.

16. In a device of the character described, in combination, a writing platen for record strips, strip guiding means positioned rearwardly of the platen to effect a turn in the strips transverse to said platen relatively rearwardly thereof, a strip checking device including a strip penetrating member mounted for reciprocation longitudinally of said platen and having its strip engaging extremity directed longitudinally of the platen toward said strip turn so as to engage and disengage the strips upon longitudinal reciprocation of said penetrating member, yielding means for yieldingly urging said penetrating member into strip penetrating controlling position at said strip turn, and a manual controlling member for said strip penetrating member operatively connected to the latter and positioned relatively forwardly of said platen, said manual controlling member having upper and lower strip severing edges and having a passageway therebetween for receiving the forward ends of the strips so as to expose the latter for grasping when operated to release said strip checking device.

LOUIS F. HAGEMAN.
